United States Patent Office

Des. 230,266
Patented Feb. 5, 1974

230,266

HOUSE OR SIMILAR ARTICLE

James Reid Thomson, 705 N. 25th St.,
Philadelphia, Pa. 19130

Division of design application Ser. No. 22,894, May 8, 1970, now Patent No. 222,130, which is a continuation-in-part of abandoned application Ser. No. 19,606, Oct. 17, 1969. Divided and this application July 8, 1971, Ser. No. 160,995

Term of patent 14 years

Int. Cl. D25—03

U.S. Cl. D13—1 A

FIG. 1

FIG 6

FIG. 7

FIG. 8

FIG. 1 is a top plan view thereof;

FIG. 2 is a side elevational view thereof;

FIG. 3 is a diagonal elevational view thereof;

FIG. 4 is a diagonal elevational view of a portion thereof, parts being broken away for clarity;

FIG. 5 is a front perspective view of a modified form thereof;

FIG. 6 is a rear perspective view of the modified form thereof;

FIG. 7 is a top plan view of the modified form thereof; and

FIG. 8 is an end elevational view of the modified form thereof.

This is a division of my pending design application Ser. No. 22,894, filed May 8, 1970 now Pat. No. D. 222,130, which application is a continuation-in-part of my pending design application Ser. No. D. 19,606, filed Oct. 17, 1969 and now abandoned.

I claim:

The ornamental design for a house or similar article, as shown and described.
